CLAIM

The ornamental design for “bakeware”, as shown and described.

DESCRIPTION

FIG. 1 is a top perspective view of bakeware.

FIG. 2 is a top view of the bakeware of FIG. 1.

FIG. 3 is a bottom view of the bakeware of FIG. 1.

FIG. 4 is a right side view of the bakeware of FIG. 1.

FIG. 5 is a left side view of the bakeware of FIG. 1.

FIG. 6 is a front view of the bakeware of FIG. 1.

FIG. 7 is a rear view of the bakeware of FIG. 1.

FIG. 8 is a top perspective view of bakeware.

FIG. 9 is a top view of the bakeware of FIG. 8.

FIG. 10 is a bottom view of the bakeware of FIG. 8.

FIG. 11 is a right side view of the bakeware of FIG. 8.

FIG. 12 is a left side view of the bakeware of FIG. 8.

FIG. 13 is a front view of the bakeware of FIG. 8.

FIG. 14 is a rear view of the bakeware of FIG. 8.

FIG. 15 is a top perspective view of bakeware.

FIG. 16 is a top view of the bakeware of FIG. 15.

FIG. 17 is a bottom view of the bakeware of FIG. 15.

FIG. 18 is a right side view of the bakeware of FIG. 15.

FIG. 19 is a left side view of the bakeware of FIG. 15.

FIG. 20 is a front view of the bakeware of FIG. 15; and,

FIG. 21 is a rear view of the bakeware of FIG. 15.

1 Claim, 6 Drawing Sheets
